UNITED STATES PATENT OFFICE

HERMAN J. HAMMERLY, OF WALLINGFORD, CONNECTICUT, ASSIGNOR TO THE TRUMBULL ELECTRIC MANUFACTURING COMPANY, OF PLAINVILLE, CONNECTICUT, A CORPORATION OF CONNECTICUT

DOUBLE-THROW KNIFE SWITCH

Application filed June 5, 1929. Serial No. 368,649.

This invention relates particularly to enclosed electric switches of the double-throw type in which the pivotally mounted switch blades are arranged to be moved by an external operating handle so as to engage either of two sets of co-operating stationary contacts positioned at opposite sides of the posts on which the blades are mounted.

One object of my invention is to provide a double-throw switch having detachable cross-bar connections between the blades and the operating member so arranged that the switch may be secured in or removed from the enclosing box without disturbing the operating member and so that the cross-bar members are secured in operable position solely by securing the switch base in position in the box.

Another object is to provide a novel form of double-throw switch blade which is particularly adapted for use in connection with quick-make and quick-break mechanism for the reason that the substantially parallel contact portions of the blade allow for applying the quick-make movement to the blade long before the blade has approached its co-operating stationary blade and for applying the quick-break movement to the blade before the blade has separated from its co-operating stationary contact in the circuit opening movement.

Another object is to provide a detachable cross-bar construction in which the cross-bars are secured in position solely by the usual assembly of the switch per se with the enclosing box and the operating member and in which construction all of the usual screw or rivet means of attaching the cross-bars are eliminated.

Another object is to provide a novel form of double-throw switch blade in which the two branches or contact arms are spaced approximately parallel with respect to each other and very much nearer together than has previously been possible thus allowing for a greater operating movement and a greater separation of the contact rupturing parts when the switch is in the off position.

Another object is to provide a switch

blade of the preceding description having a novel form of cross-bar connector which also functions to insulate the operating crank from the branches or arms of the blade.

Another object is to provide a practical cross-bar construction which is unusually neat, cheap and sturdy and which construction does not obstruct the full view of the switch parts in any of its positions.

In the drawings, my invention is shown as applied to a quick-make and quick-break switch of the form shown in my co-pending application Ser. #293,675 but, features of my invention may be applied to a manually operated switch which has a rigid connection between the switch blades and the operating member.

In the preferred form the switch blade members are forked and two insulating bars connecting the members are arranged between the two branches of each blade. The switch operating member is pivotally supported in the box independently of the other switch members and its crank portion is located between the two insulating bars.

Fig. 1 is a perspective view of a switch of one form embodying my invention, the cover of the box being open and partially broken away.

Fig. 2 is a perspective view of the forked blades and the insulating bar connection between the crank and blades.

Fig. 3 is a sectional view and side elevation of the switch parts. The box 5 and cover 6 may be of any suitable construction.

Figs. 4 and 5 illustrate the difference between my novel double-throw blade and the old well-known type which it is intended to displace.

The conducting parts of the switch are mounted on insulating base 7 which is suitably secured in the box. The switch may be constructed to take care of any number of poles of a circuit. The form shown is intended for controlling an ordinary two wire or double pole circuit. Each unit has a central post 8 to which is pivoted a movable switch member 9 having two blades or arms 10 and 11 spaced apart from each other and

adapted to engage the upper and lower jaws 12 and 13 respectively.

An operating member 14 is pivotally supported within the box and has a crank portion located between the insulating cross bars 15 and 16. These insulating bars are held in position between the respective switch members by means of projections 17 and recesses 18. These insulating bars serve 10 to insulate the blades from the operating crank and to connect the adjacent switch blades and are themselves held in place by the presence of the crank portion of the operating member.

15 The operating handle 20 on the outside of the box may be of any suitable construction and connected to the crank 14 on the inside in any suitable manner.

20 Preferably, however, I employ suitable quick-make and quick-break mechanism including the oscillating member 21 and the throwing springs 22 and 23 so as to open and close the circuit with a snap action. This construction is of the double throw 25 type so that one circuit is closed when the switch member 9 is in contact with the jaws 12 and similarly another circuit is closed through the jaws 13 when the switch member 9 is in the opposite position to that 30 shown in Fig. 1.

When the switch is of the quick-make variety I prefer to provide an abutment 24 between the switch units adapted to function as a stop and to receive the impact of the 35 insulating bars 15 and 16, respectively, when the circuit is closed.

The insulating bars 15 and 16 and the abutment 24 are preferably of fibre or the like so that they have insulating characteristics and also are somewhat resilient and 40 thus capable of cushioning and distributing the powerful impact without danger of chipping or cracking the base. There is considerable resiliency in the crank itself 45 and as the abutment 24 is midway between the opposite ends of the crank, a considerable resilience is provided by the crank itself. Although the axis of the crank is supposed 50 to coincide with the axis of the pivoted switch members, it will be seen that absolute centering is not essential because of the nature of the connection between the crank and the switch members. The cross bar of 55 the crank 14 and the insulating bars 15 and 16 may slide with respect to each other so there is no tendency of the parts to bind when in action, even when the crank and switch members are not coaxial.

By referring to Fig. 3, it will be noted 60 that the arm 10 of the blade 9 is in full contact with the stationary contact jaw 12 and is parallel with the surface of the switch base and that the arm 11 of the blade is also in a relatively parallel position.

65 When the switch is thrown to its other

contact making position, the relative positions of the blade arms is, of course, reversed.

When the switch is in the intermediate or off position, the blade arms 10 and 11 project at right angles to the base.

Because of the foregoing arrangement, it is necessary that the connecting end of the blade arms be pivoted at a point midway between the arms therefore either a comparatively high hinge post must be provided or, if a regular hinge post be used, it must be supported on a corresponding high plane.

I have provided an operating crank having its bearings in line with the hinge post 80 centers so that the crank does not "creep" or change its relative position with respect to the cross-bar members during its operating movement.

Among the advantages of this novel blade 85 are that it provides for a maximum contact breaking movement and that it allows for ample "pick-up" movement of the quick-break means before the switch operates.

With this construction it is possible to 90 remove the screws which secure the switch base to the box and slide the switch down so as to disengage the connecting bars 15 and 16 from the crank 14 without dismounting the crank. Obviously the switch may be inserted in the box and connected with the crank in a reverse order. It will be seen 95 that the insulating cross bars are positively secured in operative position without requiring any screws, rivets or assembling operations.

A comparison between Figs. 4 and 5 illustrates one of the advantages of my novel 100 design of double-throw switch blade over the old and well known form. It has been 105 customary to make blades of this type substantially as shown in Fig. 5 with one blade 10' extending at approximately ninety degrees to the other blade 11' and it will 110 readily be seen that, when the switch is moved to off or neutral position, the blades will have moved only forty-five degrees.

In Fig. 4, the blades are shown in the off or neutral position and it will be seen that the blades must move full ninety degrees 115 from either of the on positions to the off position.

This comparatively great operating movement is made possible by my substantially 120 parallel type of blade. It results in a much greater separation of the contact parts in the switch opening movement and it allows for the application of a substantial quick-make and quick-break mechanism which it is difficult to obtain in the construction shown in 125 Fig. 5.

It should be understood that various 130 changes in construction and arrangement may be made without departing from the spirit or scope of my invention.

I claim:

1. A double throw switch including a central post, a forked switch member hinged thereto and having two spaced apart and substantially parallel blades, stationary contacts adapted to receive said blades, a pivoted operating crank and insulating members on opposite sides of said crank interlocking with said blades.
2. In a double throw switch, a number of hinged switch blades, two spaced insulating bars for connecting said switch blades together and an operating member having a crank portion mounted between said insulating bars.
3. In a switch, a number of pairs of stationary contacts, a hinged switch blade mounted between each respective pair of contacts, an operating crank, insulating bars interposed between said crank and portions of the respective switch blades and an insulating abutment adapted to receive the operating impact of said insulating bars.
4. In a double throw switch a pair of pivoted forked switch members each having two spaced apart and substantially parallel blades, stationary contacts adapted to receive said blades, an operating crank and insulating bars on opposite sides of said crank between said blades and laterally connecting said blades.
5. A switch including a number of hinged switch blades, a pair of insulating bars securing said blades together in spaced relation and an operating crank having a detachable connection with said insulating bars for securing said bars in position.
6. A switch including a base, a number of pairs of stationary contacts on said base, a hinged switch member mounted on said base between each respective pair of contacts, an operating crank, insulating bars connecting said switch member with said crank, and an insulating abutment supported on said base and adapted to receive the operating impact of said insulating bars.
7. In a safety switch, a box, an insulating base detachably mounted in said box, a double throw switch blade mounted on said base and having two spaced contact arms, an operating crank pivoted in said box, and insulating cross bars interposed between said crank and the arms of said switch blade.
8. A switch including a number of hinged forked switch blades, two spaced insulating bars connecting the respective switch blades together and an operating member having a crank portion operably secured between said insulating bars.
9. A switch including a number of pairs of stationary contacts, a forked switch blade pivotally mounted between each respective pair of said contacts, an operating crank, two insulating bars on opposite sides of said
